UNITED STATES PATENT OFFICE.

OLLIE E. MOTT, OF ADRIAN, MICHIGAN.

SUSPENDER CONSTRUCTION.

Application filed March 7, 1921. Serial No. 450,184.

To all whom it may concern:

Be it known that I, OLLIE E. MOTT, a citizen of the United States of America, residing at Adrian, in the county of Lenawee 5 and State of Michigan, have invented certain new and useful Improvements in Suspender Constructions, of which the following is a specification, reference being had therein to the accompanying drawings.

10 This invention relates to improvements in suspender construction.

In suspender structures wherein the elasticity is provided by the use of a loop and spring structure, it is the practice to locate 15 the spring or springs on the loop formation, with the spring-carrying portion of the loop extending within a pocket-like formation of the webbing, a portion of the loop projecting from the pocket, such projecting portion 20 carrying the means by which the buttoning element is detachably secured to the loop. The projecting portion of the loop may be the ends of the loop or it may be an intermediate portion of the loop, depending on 25 the general type of structure employed, but in either case the attaching means is secured to the projecting portion. Since it is desirable that such attaching means be as compact as possible, it is the practice to locate 30 the lower end of the projecting portion—whether it be the two ends or the intermediate portion—in an attaching element or clip by which the cord portions are gripped in proximity to each other—generally side-by-side—the clip carrying the means by 35 which the buttoning element is secured in position.

Owing to the fact that the clip-secured 40 portion of the loop is of such compact dimensions, and the presence of the connecting means, there is a tendency at times to set up the characteristics of a twisting action, effective more or less on the projecting portion of the loop, in presence of pulling 45 strains which are applied in various forms in use through the movements of the body of the wearer of the suspenders. Such twisting characteristics not only provide discomfort to the user but also tend to make 50 the structure less efficient through the changed characteristics in the strain application due to the presence of the twist tendency.

I have found that this twist tendency is due more or less to the fact that the structures employed for connecting the loops to the buttoning element—generally a cord—are of such formation that the pulling strain on the loop end is applied in a direction such as will place a straight pull on the 60 loop. For instance, the portion of the attachment over which the buttoning cord passes is located either in front or in rear of the plane of the loop itself, due to the fact that the connections are so arranged 65 for detachment that this cord face is carried to one side or the other of such plane, depending on the characteristics of the detaching structure. I have found that where this cord face—the face over which the buttoning cord passes—extends in the plane of the 70 loop itself, the pulling strain is made effective without the twisting tendency being set up; in fact, the strain tends to prevent such tendency. 75

While it is possible to meet this condition through the use of a flexible connecting means, in which case there is more or less compensation possible, such connections are not applicable for use in connection with 80 suspender structures having this general loop characteristic, since the required width of webbing is such as to be greater than the distance desired between the strand-like portions of the projecting part of the loop. 85 Hence, the practice is to employ metallic connections, and these are generally in the form of disengageable parts, an arrangement which sets up this off-set relation of the face over which the buttoning cord 90 passes.

The present invention is designed to overcome these objections by providing a connecting element between the loop and the buttoning cord, arranged to permit ready 95 detachment of the buttoning cord, and at the same time provide a location of the cord or working face of the connection such as to place the pull strain in the plane of the loop itself. A further object is the production of 100 a connecting means which is simple and efficient in operation, durable in construction, readily applied, and which can be manufactured at a relatively low cost.

To these and other ends, the nature of 105 which will be readily understood as the in-

vention is hereinafter disclosed, said invention consists in the improved construction and combination of parts hereinafter fully described, illustrated in the accompanying drawings, and more particularly pointed out in the appended claim.

In the accompanying drawings, in which similar reference characters indicate similar parts in each of the views,—

10 Figure 1 is a view in elevation of a suspender end showing one embodiment of the present invention applied thereto.

Fig. 2 is a detail perspective view showing the connection of Fig. 1 in position.

15 Fig. 3 is a detail view, partly in elevation and partly in section, of the parts shown in Fig. 2.

In Figure 1, 5 represents a suspender end formed of webbing, said end carrying a portion 5^a folded upon itself to produce a pocket-like formation into which the cord loop 6 extends, the latter carrying springs 7 positioned in such manner that when the projecting portion of the loop is drawn, as 20 in use, the springs 7 will be compressed, the arrangement providing for the elasticity of the suspenders; the parts 5 and 5^a are connected by a suitable slide member 5^b. In the particular form shown, the loop ends 25 are contained within the projecting portion, but it will be understood, of course, that these ends may be reversed in position so as to locate them within the pocket, the middle portion of the length of the cord forming 30 the loop being doubled to provide two strands—connected in such case—having the characteristics of the ends shown in the drawing.

8 indicates the buttoning element, shown 40 as a cord, having the usual buttoning loops 9.

10 indicates the connecting element shown as an integral structure, one end of which is shaped to be secured to the projecting portion of the loop 6, the opposite end being 45 arranged to receive the cord or provide a working face for element 8.

As shown in Figs. 2 and 3, the loop-attaching end 10^a is of a formation such as 50 will permit the loop to be secured with the strand-like parts lying side by side, a simple way of producing this being to employ wings which are bent over upon the strands and clamped in position; or this end may be formed to receive the loop ends and then pressure applied to clamp the ends of the loop in position.

60 The cord or working face 10^b is located between two parts 10^c and 10^d, the face 10^b joining these parts and being curved both longitudinally and laterally, these parts having characteristics of a hook, the length of the face 10^b being sufficient to provide the proper support for the cord 8 and permit its proper working when the suspenders are 65 worn. Part 10^d forms the lip of the hook

and part 10^c preferably carries a raised portion 10^e which, in co-operation with the lip 10^d acts to retain the cord 8 within the hook, although permitting ready disengagement by reason of the yield of lip 10^d when 70 cord 8 is being forcibly removed or entered.

As shown, part 10^c and end 10^a are joined by a portion 10^f which is inclined to part 10^c, this arrangement placing part 10^c off-set with relation to the plane of the 75 loop end formation. This offsetting is preferably of such character as to place working face 10^b in the plane of loop 6; that is, the length of cord 8 which extends over face 10^b is positioned in the plane in which loop 6 80 extends, this being shown more particularly in Fig. 3.

As a result, the strains placed on loop 6 in use of the suspenders are applied in the plane of the loop itself, and hence in a direction which will permit free movement of the loop through the eyelets at the bottom of the pocket, as well as will permit proper expansion and compression of springs 7 without liability of forcing the pocketed 85 portion of the loop and springs out of such plane and into pressure contact with the walls of the pocket. And since the pull is 90 in such plane there is no tendency to twist the projecting portion of the loop either 95 through the action of the buttoning cord on face 10^b or through the location of the eyelets at the bottom of the pocket out of the plane of the direction of strain application. 100

While I have disclosed a preferred embodiment of the invention, it will be readily understood that changes and modifications therein may be found desirable or essential in meeting the exigencies of use, and I desire 105 to be understood as reserving the right to make any and all such changes or modifications as may be found desirable or essential, in so far as the same may fall within the spirit and scope of the invention as 110 expressed in the accompanying claim.

Having thus described my invention, what I claim as new is:

In suspender construction, wherein the webbing carries a pocket to receive a loop portion with its ends projected from the pocket and with the loop portion movable relative to a wall of the pocket in use to vary the projected length of the ends of the loop portion, a buttoning element, and means for operatively and detachably connecting the loop portion and the buttoning element, said means comprising a rigid one-piece member having a portion formed to receive and embracingly clamp the projecting ends of the loop portion to place them in secured permanently-positioned parallel relation in the direction of loop projection, said member carrying a face for supporting the buttoning element, said face being posi- 115 120 125 130

tioned to locate the buttoning element portion which contacts therewith to lie in the plane of such secured ends of the loop portion, whereby the strains of use will maintain the ends of the loop portion in the general plane of such loop portion and free from material transverse movement out of such plane and permit freedom of move-

ment of the loop portion relative to the wall of the pocket through which it extends. 10

In testimony whereof I affix my signature in presence of two witnesses.

OLLIE E. MOTT.
